UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A SHIN-PIECE FOR PLOWS.

SPECIFICATION forming part of Design No. 28,334, dated March 1, 1898.

Application filed December 31, 1897. Serial No. 665,253. Term of patent 14 years.

To all whom it may concern:

Be it known that I, GEORGE W. REAM, a citizen of the United States, residing at Canton, in the county of Stark and State of Ohio, 5 have invented and produced a new and original Design for a Shin-Piece, of which the following is a specification.

In the accompanying drawings, Figure 1 is a perspective view of my new design for a 10 shin-piece for plows. Fig. 2 is a rear view of the same. Fig. 3 is a plan view showing it as it appears when on the plow, and Fig. 4 is a rear view a quarter-turn from the position of Fig. 2.

15 The leading feature of the design is in the configuration or outline of the shin-piece. As shown in Figs. 1 and 3, the face A is curved from top to bottom, and the edges B C are formed on different curves, so that the lower

edge D is of greater extent than the upper 20 edge E. From the edge C the wall of the shin-piece extends rearwardly at an acute angle, as shown in Fig. 3, and where it joins the body part at the rear an abrupt shoulder F is formed, as shown in Fig. 4. A perforated 25 ear G projects outwardly on one side of the shin-piece and at the corner H a projection I extends in line with the rear surface of the body portion.

What I claim is—

30 The design for a shin-piece for plows as herein shown and described.

In testimony whereof I affix my signature in presence of two witnesses.

GEORGE W. REAM.

Witnesses:

W. H. CAVNAH,
JOS. H. MILLER.
